ELECTRICALLY COIN-OPERATED CHAIR

Jefferson D. Fowler and Ralph A. Vaughn,
Los Angeles, Calif.

Application March 25, 1946, Serial No. 656,850

6 Claims. (Cl. 155—188)

1

This invention relates to chairs, and more particularly to a chair having means for preventing access to, and use of the chair except under certain prearranged conditions.

In general, the chair is intended for use in such establishments as shine parlors, barber shops, and any other place where a service is rendered to the occupant of the seat in exchange for a monetary consideration. The chair comprises broadly a seat, a hinged cover for the seat movable between a closed position in which it prevents access to the seat and an open position in which it permits access to the seat and also serves as a back rest for the occupant of the chair, means for locking the cover in open and closed positions, and means for moving the cover between its open and closed positions. The locking means for maintaining the cover closed is controlled by coin operated means such as a coin controlled electric switch so that the chair can be used only after a coin or a certain combination of coins has been deposited. Means are also provided for closing the cover after the occupant steps down from the chair.

Thus the proprietor of the establishment is assured of receiving a given sum of money from each occupant of the chair and the only money which need be given by the customer to the operator, that is, the shine boy or barber, would be the tip.

Accordingly, it is an object of the invention to provide a chair to which access is prevented except after predetermined conditions such as the deposit of a coin have been fulfilled.

Another object of the invention is to provide a chair having a movable cover which, when in closed position, prevents access to the chair, and when in open position not only permits access to the chair seat but also serves as a back rest for the occupant of the seat.

Still another object of the invention is to provide a chair of the type referred to in the preceding object and which includes means for automatically unlocking and moving the cover to the open position upon the occurrence of a predetermined event such as the deposit of a coin, and for thereafter closing the cover after the occupant leaves the seat.

A further object of the invention resides in the provision of electrical operating means for accomplishing the above objects of the invention.

These and other objects of the invention will be apparent from the following specification and the accompanying drawings, in which:

Fig. 1 is a perspective view of the chair with the cover closed;

2

Fig. 2 is a perspective view of the chair with the cover open;

Fig. 3 is a vertical sectional view of the chair showing the operating means therefor;

Fig. 4 is a diagrammatic electrical circuit for operating the chair; and

Fig. 5 is a perspective view showing the cover latched in open position and showing the motor and cable mechanism.

10 In the drawings is shown a preferred embodiment of the invention as applied to shoe shine chairs. It is to be understood that the invention may be adapted to other types of chairs by slight changes.

15 As shown in Figs. 1 through 3, the chair comprises a body portion 10 having cushioned arms 11 between which is positioned a cushioned seat 12. A drawer 13 for shoe shine equipment is provided in the lower front part of the body portion 11 and a coin slot 24 is provided in one arm.

20 A floor or step portion at the front of the chair supports a pair of brackets 15 on which are pivotally mounted footrests 16. As best shown in Fig. 3, the footrests are free to be rotated to a near vertical position by movement of the cover, which will be described presently, to its closed position. The footrests are weighted in the heel portion at 17 so that they automatically return to their horizontal operating position as soon as they are released by movement of the cover to its open position.

25 30 35 40 45 A cover 18 is pivoted at 19 to the body 10 and comprises a back portion 20 suitably cushioned internally at 21 and a top or canopy portion 22 similarly cushioned at 23. When in closed position, the back portion 20 of the cover lies immediately above the seat 12 and the top portion 22 of the cover encloses the front of the chair. When in open position, the back portion 20 of the cover forms a back rest for the occupant of the chair while the top portion 22 forms a canopy over the occupant. Suitable lights 26 may be provided in the cover in proximity to windows 27 in the cover to provide light for the occupant and may be controlled by switches (not shown) closed by opening of the cover.

40 45 50 55 Latch receiving openings 28 and 29 are provided in the cover as shown in Figs. 3 and 5 to cooperate with latches 30 and 31 mounted on the body portion 10 of the chair and operable by solenoids 30a and 31a. These latches are resiliently urged into latching position and have a beveled upper front edge so that they are cammed out of the way by movement of the cover into contact with the latches. As soon as

the latch opening 28 or 29 is in alignment with the corresponding latch, the latch automatically slides into engagement with the opening to retain the cover in the open position in the case of latch 31 or in closed position in the case of latch 30. When the solenoid 30a or 31a for operating one of the latches 30 or 31 is energized, it withdraws the latch from the corresponding opening 29, 30 and frees the cover for movement away from the position in which it had been latched prior to operating of the solenoid. The operation of solenoids 30a, 31a will be discussed more fully presently in the discussion of the electric operating circuit shown in Fig. 4.

The cover 20 is moved between its open and closed positions by a reversible electric motor 35 which rotates a spindle 36 about which is wound a cord or cable 37. The cable passes over suitable pulleys 38 and is attached at its ends to an arm 40 fixed to the cover 20 so that movement of the cable effects movement of the arm 40 and thereby movement of cover 20. A suitable weight 41 may be provided on the arm 40 to insure tight closing of the cover 20. It is obvious that rotation of spindle 36 in the direction of arrow A in Fig. 3 will open the cover while rotation in the direction of arrow B will close the cover.

An electrical circuit for operating the chair is shown in Fig. 4 but it is to be understood that numerous modifications of this circuit can be made without departing from the inventive concept.

In Fig. 4, a source of current 50 provides power to operate the mechanism and a master switch 51 is placed in the circuit in series with the current source so that the entire device can be controlled by the proprietor as at the opening and closing of business. Switch 51 may be a gang switch controlling all of the chairs in the establishment or a control panel may be provided having a switch 51 for each chair.

The remainder of the circuit may most conveniently be described as two circuits, an opening circuit for running motor 35 in direction A to open the cover, and a closing circuit to run motor 35 in direction B to close the cover.

The opening circuit includes a switch 55 which is actuated by spring 55a and by cover 20 so that the switch is closed by movement of the cover to closed position and is opened by spring 55a when the cover is opened. Conventional means such as a dashpot (not shown) is provided for delaying opening of switch 55 to ensure that the cover is opened completely before the switch opens and disables the motor operating circuit. If desired, positive means actuated by cover 20 may be provided to open switch 55 when the cover reaches open position.

The opening circuit further includes a motor operating switch 56 which is normally open and which is closed by energization of a solenoid 57. The solenoid 57 is controlled by a coin controlled switch 58 of any conventional type wherein a switch is closed when a coin is inserted in the device. Also in the circuit with solenoid 57 is latch operating solenoid 30a so that the solenoid 30a is energized and latch 30 withdrawn when solenoid 57 is energized.

If desired, a counter 59 of any conventional type may be provided so as to be operated by coin operated switch 58. A bypass switch 60 may be provided so that the proprietor can open the chair without depositing a coin for test purposes or to permit use of the chair by an occupant who

was called away before completion of his shine.

A switch 61 may be provided for operation by solenoid 57 along with switch 56, and when closed sets into operation any suitable timer which will inform the proprietor when the chair has been open an unusually extended length of time.

Thus, with switch 55 closed by the cover 20 being in closed position, a coin dropped into switch 58, or operation of switch 60, energizes solenoids 57 and 30a. Solenoid 30a withdraws latch 30 and solenoid 57 closes switch 56 setting motor 35 into operation in the direction of arrow A to open the top.

The closing circuit includes a switch 65 operated by the cover 20 and spring 55a so that the switch is open when the cover 20 is closed and is closed by spring 55a when the cover is opened. This switch serves when open to disable the entire closing circuit and, when closed by spring 55a on opening of the cover 20, to permit operation of the closing circuit.

The closing circuit further includes a switch 66 operated by a solenoid 67 so that switch 66 is closed when the solenoid is energized and is opened by suitable resilient means (not shown) when the solenoid is not energized.

The solenoid 67, preferably of the conventional delayed operating type, is operated by a circuit which includes, in series connection, switch 65, latch solenoid 31a, and a series of switches 68, 69, 70, and 71 positioned respectively one in each arm cushion, one in the seat cushion 12, and one in the back cushion 21. Switches 68, 69, 70, and 71 are normally closed switches and are movable by the body pressure of the occupant of the seat to open position. By means of these switches, the circuit for operating solenoid 67 is maintained open as long as the body or an arm of the occupant presses against any one of the cushions and thereby opens the switch in that cushion. When the occupant leaves the chair, all of the cushion switches close and, switch 65 being closed by the cover being open, solenoid 67 is energized. After the delay provided in solenoid 67 to give the occupant adequate time to leave the chair, switch 66 is closed and the motor operated to close the cover. Inasmuch as latch solenoid 31a is in series with solenoid 67, the latch 31 is withdrawn by solenoid 31a prior to the closing of switch 66 and operation of motor 35 to close the cover.

If desired, switches 68, 69, 70, and 71 may be rearranged in the circuit so that only one switch being open would not maintain the cover open, but a preselected combination of switches such as the seat switch and one arm switch would have to be open to maintain the cover opening circuit disabled.

As shown in Fig. 5, a dashpot 80 or other buffer mechanism may be provided to delay the closing movement of the cover.

To summarize briefly the operation of the device, beginning with the cover 20 closed, master switch 51 closed, and switch 55 closed by the cover, a coin is dropped into slot 24. The coin closes switch 58 which completes the circuit of solenoids 57 and 30a. Solenoid 30a withdraws latch 30 which had latched cover 20 closed. Solenoid 57 closes switch 56 and, if desired, switch 61, thus setting the timer into operation and starting motor 35 in operation to rotate spindle 36 in the direction of arrow A in Fig. 3. Rotation of the spindle operates the cable and pulley arrangement shown in Fig. 3 and through arm 40 moves cover 20 to its open position where it is retained by latch 31. After a short delay, switch

55 is opened by spring 55a disabling the opening circuit.

The opening of switch 55 closes switch 65 of the closing circuit after a short delay which gives the customer time to position himself in the seat. When the occupant is in the seat, one or more of switches 68, 69, 70, 71 is opened by pressure of the body or arms of the occupant on the cushions, thereby opening the operating circuit of solenoid 67.

After the shine is completed and the customer steps down from the chair, the release of the pressure on the cushions permits springs 68, 69, 70, 71 to close and, switch 65 being closed as heretofore described, solenoids 67 and 31a are energized.

Solenoid 31a withdraws latch 31 which maintained the cover open and solenoid 67 closes switch 66 after a short delay provided for safety purposes and the closing circuit is completed to run motor 35 and rotate spindle 36 in direction B in Fig. 3, thereby closing the cover.

When the cover reaches the closed position, it opens switch 65 de-energizing motor 35, and closes switch 55, placing the opening circuit in readiness. Latch 30 engages opening 28 in the cover and the cover is thereby locked shut until another coin is inserted.

It will be apparent from the description of the operating circuit that the chair may be used as an ordinary shine chair simply by opening master switch 51 while the cover 20 is latched in its open position. With switch 51 open, the movement of customers into and out of the chair will have no effect on the latches and the motor due to the fact that no current will be supplied to the circuit for operating these elements.

It is obvious that we have described and illustrated a simple and foolproof chair and operating mechanism. It should be borne in mind, however, that we have described only a preferred embodiment of our invention susceptible of other embodiments without departing from the scope of the invention as defined by the appended claims.

We claim:

1. A chair comprising a seat, a cover for the seat, and mechanism mounting said cover for movement between a closed position in which it prevents access to said seat and an open position in which said cover serves as a back rest for the occupant of the chair, a reversible electric motor operable to move said cover between said positions, an electric circuit controlling the operation of said motor in either direction, coin controlled switch means in said circuit for controlling operation of said motor in one direction to move said cover from said closed position to said open position, and switch means in said circuit and positioned in portions of said chair contacted by the occupant for deenergizing said motor as long as the chair is occupied to prevent operation of said motor in the opposite direction for movement of said cover from said open position to said closed position during occupancy of the chair.

2. A chair as set forth in claim 1 in which means are provided for latching said cover in said open and closed positions.

3. A chair as set forth in claim 1 in which means are provided for latching said cover in said open and closed positions and in which said motor control circuit includes means for rendering said latching means inoperative.

4. A chair comprising a seat, a cover for the seat, and mechanism for mounting said cover for movement between a closed position in which it prevents access to said seat and an open position in which said cover serves as a back rest for the occupant of the chair, a reversible electric motor, means operatively connected to said cover and operable by rotation of said motor in one direction for moving said cover from closed to open position and operable by rotation of said motor in the opposite direction for moving said cover from open to closed position, electric controlling circuits for said motor, latches for maintaining said cover in said open and closed positions, and electric means in said circuits for rendering inoperative the latching means maintaining the cover in closed position concurrently with operation of said motor to open said cover and for rendering inoperative the latching means maintaining the cover in open position concurrently with operation of said motor to close said cover.

5. A chair comprising a seat, a cover for the seat, and mechanism mounting said cover for movement between a closed position in which it prevents access to said seat and an open position in which said cover serves as a back rest for the occupant of the chair, a reversible electric motor, means operatively connected to said cover and operable by said motor for moving said cover between said positions, an electric circuit for operating said motor in one direction to close said cover, an electric circuit for operating said motor in the opposite direction to open said cover, and switch means operable by said cover for disabling said cover opening circuit when said cover is in said open position and for disabling said cover closing circuit when said cover is in its closed position.

6. A chair comprising a seat, a seat access controlling member movable between a closed position blocking access to the seat and an open position permitting access to the seat, retaining means for holding said member in each of said positions, electrically driven power means for moving said member between said positions, a control circuit for said power means, switch means in said circuit and positioned in portions of the chair contacted by an occupant for rendering said power means inoperative as long as the chair is occupied, and means in said control circuit for rendering said retaining means inoperative.
